W. DALTON

RAILROAD TRACK STRUCTURE

Filed Sept. 20, 1926

Patented Jan. 24, 1928.

1,657,241

UNITED STATES PATENT OFFICE.

WILLIAM DALTON, OF GLENVILLE, NEW YORK.

RAILROAD-TRACK STRUCTURE.

Application filed September 20, 1926. Serial No. 136,447.

This application is a continuation in part of my application Serial No. 101,259, filed April 12, 1926. It relates to railroad track structures and especially to railroad track structures wherein the ties are made from metal.

One object of the invention is to provide an improved form and construction of metal railroad tie which can be provided at low cost, which furnishes a good support for the rail, and which, by reason of its construction, enables the rail to be fastened to it in an improved and advantageous manner.

Another object of the invention is to provide an improved tie structure wherein the major portion of the tie may be made with great advantage from lengths of old or worn rail.

A further object of the invention is to provide an improved form of tie adapted to have fastened to it rails having base flanges of different widths, which means that the tie may be standardized for various weights of rails.

Other objects of the invention as well as the advantages of the invention are pointed out hereinafter, and for a consideration of what I believe to be novel and my invention, attention is directed to the following specification and the claims appended thereto.

In the drawing, Fig. 1 is a perspective view of a railroad tie embodying my invention; Fig. 2 is a perspective view showing the manner in which a track rail may be attached to the tie; Fig. 3 is a top plan view of the tie, and Fig. 4 is a perspective view of a modified form of track tie.

Referring to the drawing, Figs. 1 to 3 inclusive, the tie comprises two lengths of old or worn rail 1 and 2 which stand in spaced relation to each other and are fastened together at their ends by end plates 3 and 4. The end plates may be fastened to the worn rail lengths which form the tie in any suitable manner but preferably I weld them thereto as this provides a most efficient form of connection and one which can be provided at low cost. The end plates are in the form of angle bars, one wall of the angle bar being located beneath the base flanges 5 of the worn rail lengths and the other wall extending across the ends of the worn rail lengths. The bottom flanges of the worn rail lengths and the wall of the angle bar which is located beneath them are

welded together as is indicated at *a*. The wall extending across the ends of the worn rail sections may be or may not be welded to the rail sections as is found desirable. 60 Ordinarily, when worn rails are made into lengths they are first nicked and then broken. This leaves the ends rough and irregular in shape. However, by using angle bars, as shown, which extend beneath 65 and are welded to the bottom flanges of the worn rail lengths, I avoid any difficulties as far as the irregular ends are concerned because the bottom surface of the bottom flanges of the worn rail sections are smooth 70 and flat. The vertical walls of the angle bars 3 and 4 perform an important function in that they serve to anchor the tie in the ballast. I consider the use of angle bars for fastening together the rail lengths as being 75 an important feature of my invention.

The webs of the old rail sections are indicated at 6 and the top flanges are indicated at 7. At the points where the track rails lie on the tie, I provide supporting 80 plates 8 which lie on top of flanges 7 and are welded thereto as is indicated at 9. Supporting plates 8 are of suitable thickness and at opposite ends they are provided with rectangular openings 10 located over 85 the space between the top flanges 7 of the worn rail lengths. Openings 10, in the embodiment of the invention illustrated in the drawing, are spaced apart a distance somewhat greater than the width of the base 90 flanges of the largest rails with which the tie is intended to be used which adapts the tie when used with a rail fastening means as shown in Fig. 2, to have fastened to it any one of a number of different sizes of 95 rails. This is an important consideration in case a rail-fastening means as shown in Fig. 2 is utilized because it enables the tie to be made in a standard size adapted for use with rails having base flanges of different widths.

In connection with supporting plates 8, it will be noted that they are of a width measured transversely of the tie such that the longitudinally-extending edges of plates 105 8 terminate directly over webs 6. This serves to concentrate the load directly on the webs and to remove it from the edges of the flanges thus avoiding a tendency to cause the tie members to tilt.

By the above described arrangement, I provide a metal railroad tie which can be

2

constructed at low cost, especially when made from lengths of worn rail sections. In this connection, it will be appreciated that large numbers of worn rails are removed each year and sold as scrap material. These rails when removed, if used for making ties, are where they are to be again used as ties. My improved tie can be constructed readily at any place since no special shop equipment is required in its manufacture. As a result, therefore, in making ties according to my invention from worn rails, transportation of the worn rails to a point of manufacture is minimized which means a substantial saving in cost.

Also in constructing ties according to my invention, scrap angle irons may be used for the end plates. In this connection, any angle iron has one surface at least which is true and the bottom surface of the base flange of a worn rail is always a true surface. Thus there are provided and always available two true flat surfaces which may be fastened together. Also, any size of angle iron may be used since the only requirement is that it provide one true surface. As a result, scrap angle irons of various sizes may be used in carrying out the invention. Also, any size of angle irons may be used with any size of scrap rails. This gives great flexibility in using scrap material in the construction of the ties.

A further important advantage of my invention from a manufacturing standpoint is that the parts may be welded together with straight line welds which means that the welding can be done with a line welding machine. As shown in the drawing, the vertical flange of the angle bars is spaced from the ends of the rail lengths, it being unnecessary to fasten it to the rail lengths. The vertical flanges of the angle bars however perform an important function in that as pointed out above, they serve to anchor the tie against endwise movement.

In considering the structure shown in Figs. 1 to 3, it will be seen that the tie comprises only six pieces, two lengths of old rail, two angle irons, (which may be scrap material) and two flat tie plates. This is a minimum number of parts and enables the tie to be constructed with a minimum amount of labor. The two tie plates and the two angle irons are so distributed relatively to the two worn rail sections, the tie plates being fastened to the tops of the rail sections and the two angle irons to the bottom thereof, that there results a girder construction which lends great strength and stiffness to the tie. With this construction, there is no danger that the two rail sections which form the tie will be spread by the wheels of a train passing over them. The construction has strength substantially greater than that of a wooden tie and in addition it pre-

sents to the ballast of the roadbed a substantially greater surface so that it is capable of supporting a much greater load. In this connection it will be understood that a railroad tie distributes a concentrated axle load through the ballast to a resilient soil, and that such soil, ordinarily, is capable of supporting a load of the order of 6000 pounds per square foot. For carrying heavy axle loads, therefore, it is important that the tie should present a large supporting surface to the ballast. A tie embodying my invention presents to the ballast a surface substantially larger than that presented by a wooden tie.

My improved tie, although not limited thereto necessarily, is well adapted for use with a rail fastening means such as that illustrated in Fig. 2. Referring to Fig. 2, 12 indicates a track rail, 13 being the head of the rail and 14 being the base flange. Base flange 14 rests on tie plate 8 between openings 10, openings 10 being spaced apart a distance such that their inner edges stand in spaced relation to the outer edges of base flange 14 whereby there are provided clamping edges 15 at each side of base flange 14.

Base flange 14 is fastened to the tie by fastening means each comprising a fastener or rail clamp 16 and a keeper or wedge bar 17. Fastener 16 has a groove 18 in which clamping edge 15 is located, a vertical surface 19 for holding the rail against transverse movement, and a nose 20 which projects over the top of base flange 14 to hold the rail against vertical movement. Keeper 17 comprises a wedge shaped bar located between fastener 16 and the outer edge of opening 10. It is locked in position by a cotter pin 21 which fits into opposed grooves in the adjacent faces of the fastener and keeper. The rail is insulated from the tie by means of suitable insulating members 22 and 23 which fit under the base flange of the rail and lie between fastener 16 and the base flange of the rail.

In Fig. 4 is illustrated a modification wherein the tie plate instead of being formed from a single piece with openings in it, is formed from three pieces, a central piece 24 and two side pieces 25. These pieces are set down between the worn rail sections so they are flush with the top surfaces of them and they are welded in position as is indicated at 26. Side pieces 25 are spaced from central piece 24 so as to provide openings 27 adapted to receive rail fastening means such as those shown in Fig. 2. Otherwise the construction shown in Fig. 4 is the same as that shown in Figs. 1 to 3 and possesses substantially the same advantages. The pieces 24 and 25 may with advantage be provided with portions 28 which project under the heads of the worn rail sections to assist in furnishing a good fastening for

the pieces, and also for anchoring them against vertical movement.

While I have particularly described my invention as being carried out in connection with the use of old or worn rail lengths, it is to be understood that the invention is not limited to the use of such rail lengths as bars of any suitable cross section, such as H-bars, Z-bars or the like may be utilized if found desirable.

In accordance with the provisions of the patent statutes, I have described the principle of operation of my invention, together with the apparatus which I now consider to represent the best embodiment thereof, but I desire to have it understood that the structure shown is only illustrative and that the invention may be carried out by such other means as come within the scope of the appended claims.

What I claim as new and desire to secure by Letters Patent of the United States, is:—

1. A metal tie comprising two bars located side by side in spaced relation to each other, each bar comprising a top flange and a bottom flange united by a vertical web, and means connecting said bars together comprising angle irons located at the ends of the bars, one wall of each angle iron extending beneath said bottom flanges and being welded thereto and the other wall of each angle iron extending vertically across the ends of the bars to serve as a means for anchoring the tie against transverse movement, and rail-supporting plates welded to the tops of said top flanges in spaced relation to the ends of said bars whereby said angle irons and plates are attached independently to opposite flanges of said bars to form a girder construction, said plates being provided with openings to receive rail-fastening means.

the ends of the bars to serve as a means for anchoring the tie against transverse movement, and rail-supporting plates welded to the tops of said top flanges in spaced relation to the ends of said bars whereby said angle irons and plates are attached independently to opposite flanges of said bars to form a girder construction, said plates being provided with openings to receive rail-fastening means.

2. A metal tie comprising two bars located side by side in spaced relation to each other, each bar comprising a top flange and a bottom flange united by a vertical web, and means connecting said bars together comprising angle irons located at the ends of the bars, one wall of each angle iron extending beneath said bottom flanges and being welded thereto and the other wall of each angle iron extending vertically across the ends of the bars to serve as a means for anchoring the tie against transverse movement, and rail-supporting plates welded to the tops of said top flanges in spaced relation to the ends of said bars and with their longitudinally-extending edges directly over said vertical webs, said plates being provided with openings to receive rail-fastening means.

In witness whereof, I have hereunto set my hand this 17th day of September, 1926.

WILLIAM DALTON.
